OF D 20•612

D20612

Design No. 20,612, dated March 24, 1891.

UNITED STATES PATENT OFFICE.

HENRY W. PARTON, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,612, dated March 24, 1891.

Application filed February 16, 1891. Serial No. 381,717. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of the body A and the border B. The body A consists of groups of conventionalized flower and leaf forms springing from a somewhat root-shaped form and upon a ground ornamented by leaves and branch work. The border B consists of groups

of conventionalized flower and leaf forms springing from a somewhat root-shaped form and upon a ground ornamented by leaves and branch work and of an inner marginal ornamentation of leaf-like forms and an outer marginal decoration containing scroll-shaped forms. 25

What I claim as new, and desire to secure by Letters Patent, is— 30

1. The design for carpets, composed of the body A, substantially as shown.

2. The design for carpets, consisting of the border B, substantially as shown.

3. The design for carpets, consisting of the body A and the border B, substantially as shown. 35

HENRY W. PARTON.
